UNITED STATES PATENT OFFICE.

CALVERT B. COTTRELL, 3D, OF WESTERLY, RHODE ISLAND, ASSIGNOR TO C. B. COTTRELL & SONS COMPANY, OF NEW YORK, N. Y., A CORPORATION OF DELAWARE.

AIR SPRING FOR RECIPROCATING-BED PRINTING PRESSES.

Application filed October 16, 1923. Serial No. 668,860.

To all whom it may concern:

Be it known that I, CALVERT B. COTTRELL, 3d, a citizen of the United States, and resident of Westerly, in the county of Washington and State of Rhode Island, have invented a new and useful Improvement in Air Springs for Reciprocating-Bed Printing Presses, of which the following is a specification.

10 The object of my invention is to provide automatic means for controlling the air spring whereby the pressure in the air spring cylinder will be dependent upon the velocity of the bed, eliminating the necessity of the 15 usual mechanical governor; the parts being so operated that after the momentum of the bed has been checked, there will be no pressure exerted against the bed driving mechanism and on the return stroke of the bed the 20 formation of a vacuum in the cylinder will be prevented. A further feature of the invention is the expansion of the pressure in the air leak passage and the provision of a 25 muffler so to eliminate the noise from the exhaust.

A practical embodiment of my invention is represented in the accompanying drawings, in which—

Fig. 1 represents in longitudinal vertical 30 section so much of a reciprocating bed printing press as will illustrate my invention.

Fig. 2 represents a detail longitudinal central section on an enlarged scale, through the piston.

35 Fig. 3 represents a section taken in the plane of the line III—III of Fig. 2, looking in the direction of the arrows.

The bed 1 of the press is reciprocated by any well known or approved means, not 40 shown herein. The air spring cylinders, carried by the bed, are denoted by 2, 2, which cylinders have open outer ends.

45 The pair of air spring pistons have their heads 3, 3 arranged in position to enter their respective air spring cylinders. The piston rods 4, 4 are fixedly carried by suitable supports 5, 5. Restricted air leak passages 6, 6 lead through the piston rods 4, 4 and open through the front of the piston heads 3, 3. 50 Continuations 7, 7 of these restricted air leak passages lead to a common muffler 8. It is desirable that the continuations 7, 7 of the air leak passages 6, 6 be of greater size than the air leak passages so as to permit the

expansion of air in said continuations, the 55 further expansion of the air being permitted in the muffler 8. This arrangement entirely eliminates the noise of the exhaust through these air leak passages and their continuations as the air spring cylinders engage their 60 respective pistons during the reciprocation of the bed.

Air relief valved passages 9, 9 are provided in the piston heads 3, 3 opening through the fronts thereof. In the present 65 instance I have shown an annular series of holes 9 forming these passages and a single disc valve 10 for the passages in each piston head. These valves 10, 10 are so arranged that the formation of a vacuum in the air 70 spring cylinders will be prevented by the opening of the valves as the air spring cylinders start to withdraw from their engagement with their respective air spring piston heads.

75 From the above description it will be seen that, as the bed reaches the limit of its movement in either direction and after its momentum has been checked by the air spring, the air leak will practically eliminate the 80 air spring and permit the driving mechanism to freely start the bed on its return movement, the air relief passages serving to prevent any drag by the elimination of the 85 possibility of forming a vacuum in the air chamber.

It is evident that various changes may be resorted to in the form, construction and arrangement of the several parts without departing from the spirit and scope of my invention; hence, I do not wish to be limited to the particular embodiment herein shown and described, but—

What I claim is:

1. In a reciprocating bed printing press, 95 an air spring cylinder carried by the bed, an air spring piston, a restricted air leak passage opening through the front of the piston head, and an air relief valved passage opening through the front of the piston for preventing a vacuum being formed within the cylinder as it is backed off the piston.

100 2. In a reciprocating bed printing press, an air spring cylinder carried by the bed, an air spring piston, a restricted air leak passage of increasing size opening through the front of the piston head, and an air relief valved passage opening through the piston

head for preventing a vacuum being formed within the cylinder as it is backed off the piston.

3. In a reciprocating bed printing press, 5 an air spring cylinder carried by the bed, an air spring piston, a restricted air leak passage opening through the front of the piston head, a muffler for said passage, and an air relief valved passage also opening 10 through the front of the piston head for preventing a vacuum being formed within the cylinder as it is backed off the piston.
4. In a reciprocating bed printing press, 15 an air spring cylinder carried by the bed, an air spring piston, a restricted air leak passage of increasing size opening through the front of the piston head, a muffler for said passage, and an air relief valved passage also opening through the front of the 20 piston head for preventing a vacuum being formed within the cylinder as it is backed off the piston.

5. In a reciprocating bed printing press, 25 a pair of air spring cylinders carried by the bed, a pair of air spring pistons, restricted air leak passages opening through the fronts of the piston heads, a common muffler for said passages, and air relief valved pas-

sages also opening through the fronts of the piston heads for preventing a vacuum being 30 formed within the cylinders as they are backed off from their respective pistons.

6. In a reciprocating bed printing press, a pair of air spring cylinders carried by the bed, a pair of air spring pistons, restricted 35 air leak passages of increasing size opening through the fronts of the piston heads, a common muffler for said passages, and air relief valved passages also opening through the fronts of the piston heads for preventing 40 a vacuum being formed within the cylinders as they are backed off from their respective pistons.

7. In a reciprocating bed printing press, 45 an air spring cylinder carried by the bed, an air spring piston, a restricted air leak passage leading axially through the piston to the front of the piston head, an annular series of air relief passages leading through the piston head to the front thereof, and a common valve for opening and closing said passages.

In testimony, that I claim the foregoing as my invention, I have signed my name this second day of October, 1913.

CALVERT B. COTTRELL, 3RD.
